UNITED STATES PATENT OFFICE.

ANDREW EPPLER, JR., OF NEWTONVILLE, ASSIGNOR TO THE EPPLER WELT MACHINE COMPANY, OF BOSTON, MASSACHUSETTS.

BOOT OR SHOE SEWING MACHINE.

SPECIFICATION forming part of Letters Patent No. 447,872, dated March 10, 1891.

Application filed September 1, 1890. Serial No. 363,735. (No model.)

To all whom it may concern:

Be it known that I, ANDREW EPPLER, Jr., of Newtonville, in the county of Middlesex and State of Massachusetts, have invented 5 certain new and useful Improvements in Machines for Sewing Welts to Uppers and Inner Soles of Boots or Shoes, of which the following is a specification.

This invention relates to boot or shoe sewing machines employing a curved needle reciprocating in the arc of a circle; and it has for its object to provide a simple and effective machine of this class in which a welt-guide is combined with the stitch-forming mechanism to hold a welt in the proper position on the upper and in which the needle is arranged to draw the welt against the upper and toward the inner sole in forming the stitches, the interlocked portions of the 15 stitches being formed within the channel of the sole, while the single-thread portions lie on the welt, so that the welt is drawn to and held closely in its proper position by the stitches and is caused to support the single- 20 thread portions of the stitches and by its superior strength and toughness prevent said portions from cutting and sinking into their support, as they would be likely to do if they were supported by the comparatively yielding 25 and insubstantial material of the inner sole.

The invention also has for its object to provide means for twisting the enchain portions of the loops of a series of single-thread chain stitches, and thereby preventing the 30 chain from raveling in the event of the breakage of any part thereof, and also preventing the enchain loops from cutting into the material in which they are formed, said material in a boot or shoe sole being the comparatively yielding and spongy leather at the bottom of the channel, which is cut to receive the chain. These results I attain by the mechanism which I will now proceed to describe.

45 Of the accompanying drawings, forming a part of this specification, Figures 1 and 2 represent side elevations of my improved machine, taken from opposite sides thereof. Fig. 3 represents a section on line 3 3 of Fig. 1, 50 looking to the right. Fig. 4 represents a section on line 4 4, Fig. 3. Fig. 5 represents a

section on line 5 5, Fig. 1. Fig. 6 represents a section on line 6 6, Fig. 1, looking toward the left. Fig. 7 represents a section on line 7 7, Fig. 1, looking toward the left. Fig. 8 represents a section on line 8 8, Fig. 2. Fig. 9 represents a side view of the looper and a portion of the needle, showing by dotted lines the course of the looper around the needle. Fig. 10 represents a section on line 10 10, Fig. 60 2. Fig. 11 represents a section on line 10 10, Fig. 2. Fig. 11 represents a section on line 11 11, Fig. 1. Fig. 12 represents a side view of the needle-carrying arm and cast-off. Fig. 13 represents a section on line 13 13, Fig. 3, 65 looking toward the left. Fig. 14 represents a section on line 14 14, Fig. 13. Fig. 15 represents a perspective view of the welt-guide shown in Figs. 13 and 14. Fig. 16 represents a perspective view of the awl and welt guide 70 and their operating-levers and a portion of a boot or shoe on a last, the said parts being in the relative positions they occupy when the awl is penetrating the work before moving laterally to feed the same. Fig. 17 represents a transverse section of a portion of the inner sole, upper, welt, and last, and a side view of a portion of the fixed channel-guide, the latter being omitted from Fig. 16 to show the welt-guide 75 more clearly. Fig. 18 represents a side view 80 of a portion of the machine, showing the movable rest that supports the boot or shoe below the stitch-forming devices and the means for locking and releasing said rest. Fig. 19 represents a section on line 19 19, Fig. 18. 85 Figs. 20 to 24, inclusive, represent perspective views showing the manner of twisting the enchain portions of the stitch-loops. Fig. 25 represents a perspective view of a series of stitches the enchain loops of which 90 are twisted, said stitches being formed in the channel of a boot or shoe sole, which, with portions of the upper and welt, are shown in section, the section being taken through the welt, the upper, and the "between substance," 95 or the part of the inner sole between the upper and the bottom of the channel in said sole. Figs. 26, 26^a, 26^b, and 26^c are detail views to illustrate the operation of the looper in carrying a loop of thread one and a half 100 times around the needle and then returning to its initial position.

The same letters and numerals of reference indicate the same parts in all the figures.

In the drawings, *a* represents the supporting head or frame, to which is rigidly attached 5 the downwardly-projecting channel gage or guide *b*, the latter being a curved and pointed finger formed, as shown in Fig. 17, to enter the channel *c*, formed in the inner sole *d*.

e represents the driving-shaft, which is 10 journaled in bearings in the frame *a*.

f represents the welt-guide proper, which is composed of the sides of a slot formed in the end of a lever *f'*, which is provided with a hub *f''*, Fig. 4, fitted both to oscillate and 15 move endwise on a tubular or hollow stud *g*, affixed to the frame *a*. The upper end of the lever *f'* carries a trundle-roll *h*, Figs. 13 and 14, which is held by the pressure of a spring *i* against an inclined rib or flange *j* on 20 a vertically-reciprocating slide *k*. Said slide, which is fitted to move between vertical guides or ways *l l*, Fig. 13, on the frame *a*, is normally raised by a spring *m*, Fig. 14, and depressed by a cam *n*, Figs. 1 and 13, on the 25 driving-shaft, said cam bearing on a trundle-roll *o* on the upper end of the slide *k*.

p represents the curved awl, which is attached to one end of a lever *p'*, the latter having two arms or branches on which are sockets or hubs *p'' p''*, one of which is fitted to oscillate on the hub *f''* of the welt-guide lever and the other on the hollow stud *g*, as clearly shown in Figs. 4 and 16, the awl-lever being thus adapted to oscillate on said stud *g*.

35 The awl-lever *p'* is provided with a slot which receives a block *q*, Figs. 1, 4, and 16, which is pivoted to a slide *r*, adapted to slide vertically between suitable fixed guides on the frame *a*, and is provided at its upper end 40 with a trundle-roll *s*, Figs. 1 and 6, which enters a cam-groove *t*, Fig. 6, in the back of the disk on which the cam *n* is formed. The downward movement of the slide *k* causes the inclined rib *j* thereon to move the welt-guide *f* away from the fixed channel-guide *b*, while the upward movement of said slide, caused by the spring *m*, moves the welt-guide toward the fixed channel-guide, said spring 45 enabling the slide to be stopped in its upward movement by the contact of the welt-guide with the shoe-upper, so that the welt-guide conforms automatically to the thickness of material between the outer surface of the upper and the bottom of the channel *c* in 50 the inner sole. The downward movement of the slide *r* moves the awl-lever *p'* to throw the awl forward in the arc of a circle toward the channel-guide *b*, while the upward movement of said slide moves the awl-lever to 55 retract the awl.

60 The welt-guide lever *f'* and the awl-lever *p'* are movable together laterally on the stud *g* to enable the awl to feed the work and return to its starting position, and to this end 65 said levers are moved on said stud in the direction required to give the awl its work-feeding movement by a lever *u*, Figs. 3 and

4, pivoted at *v* to the frame *a*, and a cam *w* on the driving-shaft bearing on a trundle-roll *x* on said lever *u*, the latter having at its lower 70 end an adjustable stud *y*, bearing on a cap *f'''*, secured upon the hub *f''* on the welt-guide lever. (See Figs. 3, 4, and 16.) The said awl and welt-guide levers are moved in the opposite direction when permitted by the recession of the cam *w* by a spring-plunger *z*, Fig. 4, which is fitted to slide in the stud *g*, and is pressed against the cap *f'''* by a spring *z'*, which is supported by an adjustable plug *z''*, screwed into one end of the stud *g*. 80

When the awl is in its work-perforating position, (in which position it is held by the plunger *z*), its point is directly opposite the point of the channel-guide *b*, so that when the awl advances to penetrate the work it 85 moves directly toward the point of said guide, the latter being arranged in the path of the awl. The result of this arrangement is that the channel-guide supports the material against the pressure of the awl, so that there 90 is no tendency on the part of the awl to displace the work or cause it to swing or turn on the channel-guide as there would be if the awl and guide were not at this time in line with each other. The forward movement of 95 the awl is stopped just before its point reaches the channel-guide, so that there is no actual contact of the awl with said guide.

95 *A* represents the needle, which is attached to an arm or lever *B*, mounted to oscillate on 100 a fixed tubular stud *C*, Figs. 10 and 12, said stud being suitably affixed to the supporting-frame. The needle is oscillated by means of a cam *D* on the driving-shaft, a lever *E*, pivoted to the frame *a* and engaged at one end 105 with said cam, and a rod *F*, connecting said lever with the needle arm or lever *B*.

110 It will be observed by reference to Figs. 1 and 2 that the needle and guard are arranged at one side of the channel-guide *b* and the 115 awl and welt-guide and looper at the opposite side, so that the needle in drawing the loops of thread and forming the stitches pulls or draws the welt inwardly against the upper and toward the inner sole. It will also be observed by reference to Fig. 3 that the plane 120 in which the needle oscillates is at the left of the point of the channel-guide, so that the needle in entering the work passes by the channel-guide without interference therewith.

125 The needle-guard *G* is attached to an arm *G'* on a rod or rock-shaft *H*, the latter being journaled in the tubular stud *C* and provided at one end with an arm *I*, Figs. 2 and 10, 130 which is connected by a rod *J* with a slide *K*, which is reciprocated vertically in ways in the frame *a* by means of a cam-groove *L*, Fig. 3, said groove receiving a trundle-roll *M* on the slide *K*. A positive oscillating motion is 135 imparted to the needle-guard by means of the cam-groove *L* and the described intermediate devices. The positive operation of the needle-guard, in contradistinction to the yielding

movement of the guard by a spring, as heretofore, is a feature of my invention, its advantage being entire freedom from liability of the needle-guard to be accidentally displaced.

5 N represents the looper or thread-carrier, which is a bent or curved finger having a thread-guiding eye N' in its lower end and which is attached at its upper end to a lever O. Said lever is pivoted at P to an arm Q, 10 formed on a three-armed lever Q', which in turn is pivoted at R to the supporting-frame. The upper arm of the lever Q' has a trundle-roll Q⁴, which is held by a spring S, Fig. 3, against a cam T on the driving-shaft, and the 15 upper end of the lever O is engaged by means of a trundle-roll U' thereon with a cam-groove U on one side of the cam T. It will be seen, therefore, that the lever O has a compound movement, one caused by its own oscillations 20 on the pivot P and the other by the oscillations of the lever Q' on its pivot R, the result of the two movements being a revolving movement of the thread-guiding eye N' around the needle, as indicated by the dotted 25 arrow in Fig. 9 and by Figs. 20 to 23, inclusive, said movement twisting the chain portions of the stitches, as presently described.

V represents a rest for the side of the lasted upper located below the channel-gage b and 30 the stitch-forming devices and arranged to bear on the upper immediately below the point where the stitches are formed. Said rest is a head or enlargement formed on a shank V', which is fitted to slide horizontally 35 in a way formed in a casing V², attached to the frame a. The shank is provided with rack-teeth V³, meshing with a pinion V⁴ on a shaft V⁵, which is journaled in the casing V². The rest V is normally pressed outwardly in 40 the direction indicated by the arrow in Fig. 18 by a spring V¹⁰, which is affixed at one end to the frame a, Fig. 1, and bears at its free end against a rod V¹¹, affixed to the shank V', so that when the shank is free to move the 45 rest is kept pressed against the upper and is adapted to stand at various distances from the fixed channel-gage b, the rest being thus adapted to conform to the varying projection of the side of the upper from the channel c. 50 The shank V' is left free to move endwise, as above described, when the needle is outside of the work, but is locked and made rigid during the portion of the forward movement of the needle which occurs when the needle 55 is penetrating the work and during the withdrawal of the needle from the work, so that the rest firmly supports the boot or shoe while the needle is in contact with it. The locking of the shank and rest is accomplished by 60 means of a dog V⁷ on a lever V⁸, which is pivoted at V⁹ to the casing V², a ratchet V⁶, attached to the shaft V⁵, the pinion V⁴ on said shaft, and an arm V¹¹ on the rod F, which 65 connects the needle-arm B with the lever E, that operates the needle-arm. When the needle is retracted and outside of the work, the connecting-rod F is in the position shown

in Figs. 1 and 18, its arm V¹¹ bearing on the lever V⁸ and holding dog V⁷ out of engagement with the ratchet V⁶. When the connecting-rod F is moved outwardly in the direction required to force the needle into the work, the arm V¹¹ leaves the lever V⁸, as shown in dotted lines in Fig. 18, whereupon a spring V¹⁰ moves said lever sufficiently to 70 engage the dog V⁷ with the ratchet, and thus lock the latter and through the shaft V⁵ and pinion V⁴ the shank V' and rest V, said parts remaining locked while the needle is entering and leaving the work. When the needle has 80 withdrawn from the work, the rod F resumes the position shown in full lines in Fig. 18 and raises the dog from the pawl, so that the rest is free to move in and out.

The operation of the machine is as follows: 85 The welt a' being placed in the welt-guide, the lasted boot or shoe is held by the operator in the position shown in Figs. 16 and 17, with the channel-guide b in the channel c of the inner sole. The awl and welt-guide at one 90 side of the channel-guide and the needle at the opposite side are now separated or at their farthest positions from the channel-guide, the awl being at this time directly opposite the point of the channel-guide, so that when 95 the awl advances it presses directly toward the channel-guide, as above stated. The machine being started, the welt-guide first moves forward until it bears against the upper and holds the welt in the proper position with 100 relation to the upper, as shown in Fig. 16. The awl then moves toward the channel-guide until it penetrates the welt, upper, and between substance. The awl and welt-guide then move laterally until the awl is in 105 line with the needle, the awl being thus caused to feed the work. The needle then advances and at the same time the awl retreats, the needle being thus caused to enter the hole made by the awl. After the needle 110 has moved forward its full stroke and while it holds the work, the looper, which when the needle first enters the work stands in the position shown in Fig. 20 at the left of the needle, commences to revolve about the needle 115 in the direction indicated by the arrows in Figs. 20, 21, 22, and 23, passing first under the needle in a direction opposite that in which the work is fed by the awl and then upwardly over the needle in the opposite direction, and then again under the needle in the same direction as before, stopping in the position shown 120 in Fig. 23 at the right of the needle after having made a complete revolution and a part of a second revolution around the needle. The 125 above-described operation of the looper is illustrated in detail in Figs. 26, 26^a, 26^b, and 26^c, in which the position of the needle is denoted by the point of intersection of the broken lines near the looper N. In these figures, 130 1, Fig. 26, indicates the initial position of the eye of the looper, which advances successively to the positions 2, 3, 4, 5, and 6 as the cams T and U advance, said looper-eye thus

moving from the position shown in full lines in Fig. 26 through the positions shown in dotted and full lines in said figure and Figs. 26^a and 26^b and stopping at or near position 5, Fig. 26^b, (at which time it has passed once and a half times around the needle,) until the needle has been retracted to draw the twisted loop held thereon into the work. From position 6 the looper moves to position 7, while the portion of the cam-groove U from point 9 to point 10 is moving past the roll U', and from point 7 the looper-eye moves in nearly a straight line through position 8 to its first position, while the cam-groove advances from point 10 to point 11 and beyond past the roll U'. This movement of the looper twists the thread around the needle above the barb thereof, as shown in Fig. 23, so that when the needle is retracted the twist will pass off from the needle and remain in the loop, as shown in Fig. 24, the result being that when the loop is interlocked or enchain with the succeeding loop and properly taken up the enchain portion will remain twisted, so that the chain of stitches will be composed of a series of twisted loops, as shown in Fig. 25. The above-described movement of the looper, first under the needle from the side toward which the work is moved by the feed, or, in other words, in a direction opposite the feeding movement or from the back side of the needle, then over the needle in the direction of the feeding movement, and, finally, again under the needle in the same direction as at the first movement, is essential to the production of the twisted loops, and is the result of a long series of experiments. Before the revolution of the looper about the needle the welt-guide is moved away from the needle to afford room for the described movement of the looper around the needle. The awl and welt-guide are at the same time given their back feed, or, in other words, are moved back to their original or starting position. After the back feed, the welt-guide moves forward to hold the work against the channel-guide, and then the needle withdraws and pulls the loop of thread surrounding it through the welt, upper, and between substance, and through the loop previously made, the needle-guard disengaging the last loop from the barb of the needle, as usual.

The provision of means, as above described, for twisting the loops forming the chain portions of the stitches is a very important feature of my invention, one advantage conferred by the twisted loops being the prevention of raveling or giving away of the series of stitches when the thread breaks at any single point, the twisted loops making each stitch in a great measure independent of the others. Another advantage of the twisted loops is the greater resistance they present to the surface on which they bear than two parallel strands laid side by side without a twist, said resistance preventing them from sinking into or indenting the comparatively soft and

spongy material found in the inner sole at the bottom of the channel cut therein. The strong tension to which the thread is subjected in taking up the loops renders the chain portions of the loops liable to cut into this material or between substance when the strands of the loops lie side by side, as usual, this liability being obviated by twisting the loops.

The described relative arrangement of the awl, welt-guide, looper, channel-guide, needle, and needle-guard, the awl, welt-guide, and looper being at one side of the channel-guide and the needle and guard at the opposite side, confers the following important advantages on the machine, viz:

First. The needle pulls the loops of the thread inwardly from the outer surface of the welt, as shown in Figs. 24 and 25, and thereby draws the welt closely to its place. Heretofore in attaching welts to uppers and inner soles by machine-stitching the needle has usually been arranged to pull the loops of thread outwardly from the bottom of the channel, and therefore has had a tendency to pull the welt and the between substance outwardly or away from the body of the inner sole. The inner sole is always damp or "in temper" during the stitching operation, so that the between substance is in a yielding condition and therefore easily pulled out of place by the tension of the thread. The welt is liable, therefore, to be displaced outwardly by the stitching operation, as heretofore usually performed; but this liability is avoided in the operation of my improved machine.

Second. The interlocked or chain portions of the stitches are formed in the channel of the inner sole and the single-thread portions are laid upon the welt. The single-thread portions, having a narrow bearing on the surface on which they rest, are more liable to cut or sink into said surface than the interlocked or chain portions. Hence if said single-thread portions were formed in the channel c, as they are by the operation of most welt-attaching machines heretofore used, they would be supported only by the comparatively spongy and yielding material of the inner sole, which, as already stated, is more easily cut into or indented by the stitches than the welt, the latter being made of the best leather obtainable. It will be seen, therefore, that I utilize the superior strength and toughness of the welt to support the single-thread portions of the stitches and prevent the loosening of the stitches, which would be occasioned by the cutting or sinking of the single-thread portions into the surface on which they rest.

The levers f' p', which carry the welt-guide and awl, oscillate on a center common to both—viz., the stud g. Hence the welt-guide always moves in the same arc with the awl and always holds the welt in the same position with relation to the needle, so that the awl will enter the welt at the same distance from the edge thereof in any position that the welt-

guide can assume. It will be remembered that the movement of the welt-guide toward the channel-guide depends upon the thickness of the between substance, and that the 5 welt-guide does not always come to a bearing on the upper at the same distance from the point of the awl when the latter is fully projected. Hence if the awl and welt-guide were mounted on different centers the awl would 10 not always enter the welt at the same distance from its edge.

It will be observed that the welt-guide is supported or held against the work with a yielding pressure by the spring *m* and the 15 slide *k* and the rib *j*, controlled by said spring when the needle is penetrating and withdrawing from the work and while the work is being fed by the awl, the welt-guide moving with the awl. After the feed movement 20 and while the awl and welt-guide are returning to their starting position the slide *k* is depressed, and the spring *i*, which is relatively weaker than the spring *m*, tends to move the welt-guide away from the work; but the force 25 of said spring is not sufficient to separate the welt-guide from the work, the welt-guide being retained in light contact with the work by the last stitch and its predecessors, said 30 stitch being in close proximity to the welt-guide. The spring *i* therefore relieves the 35 pressure of the welt-guide against the work while the welt-guide and awl are moving back to their starting-point without straining the seam by pulling the welt outwardly—a result which might be accomplished if the welt-guide were positively operated. It will also 40 be observed that the pressure of the welt-guide against the work while the needle is penetrating and withdrawing from the work enables the welt-guide to compress the material interposed between it and the fixed 45 channel-guide, and thus press the upper closely against its seat on the sole. The pressure thus exerted insures a tight seam or joint 50 between the upper and sole without requiring as strong a tension on the thread as would be required if the thread were relied upon to draw the upper to a close bearing on its seat. Hence the thread and the stitch-forming devices are relieved of much of the strain that 55 they would be subjected to if the welt-guide were not adapted to exert the described pressure.

I claim—

55 1. In a sole-sewing machine, the combination, with a fixed channel-guide, of a laterally-movable work feeding and puncturing awl, which is so located relative to said channel-guide when making its work-puncturing movement that a continuation of the line of movement of the said awl will intersect said channel-guide near its point, whereby the between substance of the work will be directly supported by said channel-guide against the 60 thrust of the said awl.

65 2. In a sole-sewing machine, the combina-

tion, with a fixed channel-guide, of a laterally-movable work feeding and puncturing awl so located relative to said channel-guide when making its work-puncturing movement that a continuation of the line of movement of said awl will intersect the said channel-guide near its point, and means for so reciprocating said awl in the direction of its length that the forward movement thereof will be arrested before the point of said awl quite reaches the channel-guide, whereby a channel-guide which will not be impinged against by the awl may be employed to support the between substance directly against the thrust of the said awl.

3. The combination, in a sole-sewing machine with a fixed channel-guide and a curved oscillating needle located when retracted at one side of said channel-guide, of a welt-guide, a curved reciprocating awl, a looper, and a horizontally-movable rest, said welt-guide, awl, looper, and rest being all located at the opposite side of said channel-guide from the said needle, and the said channel-guide being located directly in the line of the path of the awl when the latter is making its puncturing movement.

4. The combination, with a fixed channel-guide, of a welt-guide, a curved reciprocating awl, a looper, and a horizontally-movable rest, all located at one side of said channel-guide, a curved oscillating needle located when retracted at the opposite side of said channel-guide, a guard co-operating with said needle, two oscillating levers supporting said awl and welt-guide and both mounted on a common center, whereby the awl and welt-guide are enabled to work in the same arc and to move laterally together when the work is fed, substantially as set forth.

5. The combination, with the fixed channel-guide, the oscillating needle, and the needle-guard, relatively arranged as described, of a welt-guide, a curved reciprocating awl, and a looper, all located at one side of the channel-guide, two oscillating levers supporting said awl and welt-guide and mounted on a center common to both, and means for laterally reciprocating said levers to give the awl its feeding and its return or back-feed movements, as set forth.

6. The combination of the fixed channel-guide, the awl, the welt-guide, the levers *p'f'*, respectively supporting the awl and welt-guide, a fixed center or stud, on which said levers are mounted to oscillate and move laterally, independent means for oscillating said levers, and the lever *u*, cam *w*, and spring *z'*, whereby said levers are reciprocated laterally, as set forth.

7. The combination, with the fixed channel-guide, of the welt-guide, the oscillatory lever *f'*, supporting the same, the spring-supported slide *k*, having an incline *j*, adapted to normally support said lever and thereby hold the welt-guide against the work, a cam *u*, whereby

said slide is depressed to release the lever f' , and a spring i , whereby said lever is held against the incline, as set forth.

8. The combination, with the fixed channel-
5 guide and the stitch-forming mechanism, of
the movable rest V , the toothed shank sup-
porting said rest, the shaft having a pinion
engaging the teeth of said shank, a ratchet
on said shaft, a dog arranged to normally en-
10 gage said ratchet and lock the rest, and means,
substantially as described, for displacing said
dog to release the rest, as set forth.

9. In a sole-sewing machine, the combina-
15 tion, with a curved reciprocating needle hav-
ing a hook or barb and means for guiding a
welted boot or shoe in suitable relation to the
path of the said needle, of a work-feeding de-
vice to move the work at right angles to the
20 path of movement of the needle, a looper, and
mechanism to give said looper a complete
revolution and an additional half revolution
around the needle, the said looper passing
25 first under the needle in a direction opposite
the feeding movement of the work, then over
the needle in a reverse direction, and then
again under the needle in the same direction
as before, substantially as set forth.

10. The combination, with the curved barbed
needle, of the looper having a thread-guiding
30 eye, the lever O , supporting said looper, the
grooved cam U , positively operating said
lever O , the three-armed lever Q' , having an
arm Q , to which said lever O is pivoted, and
an upper arm carrying the trundle-roll Q^4 , the
35 peripheral cam T , and the spring S for hold-
ing said roll in contact with the said cam T ,

whereby a revolving motion once and a half
times around said needle is given to said
looper.

11. The combination, with the fixed chan-
nel-guide, the work-feeding awl, and the stitch-
forming mechanism, of the welt-guide and the
awl, both movable laterally relative to the line
of movement of the latter in piercing the
40 stock, a spring, and devices co-operating with
the latter for pressing the welt-guide yield-
ingly against the upper during the insertion
and withdrawal of the needle and the feeding
45 of the work, and a relatively weaker spring,
which acts on the welt-guide during the back-
ward or return movement of the awl and welt-
guide to relieve the said pressure without
straining the seam, as set forth.

12. The combination, with a fixed channel-
guide; a work-feeding or laterally-movable
50 awl, and stitch-forming mechanism, of a welt-
guide movable laterally with the awl, and
means for pressing the welt-guide against the
material at a point opposite the channel-guide
55 during the insertion and removal of the nee-
dle, whereby the parts being united are com-
pressed independently of the thread and of
the stitch-forming mechanism, as set forth.

In testimony whereof I have signed my name
to this specification, in the presence of two
60 subscribing witnesses, this 1st day of July,
A. D. 1889.

ANDREW EPPLER, JR.
